TOBACCO FEEDER FOR CIGARETTE MACHINES

John T. Dalton, Durham, N. C., assignor to Wright-Dalton Machinery Company, Incorporated, Durham, N. C., a corporation of North Carolina

Application June 24, 1935, Serial No. 28,183

15 Claims. (Cl. 131—39)

The present invention relates to improvements in tobacco feeders, and more particularly to tobacco feeders for cigarette machines and the like where the tobacco to be fed is cut in long lengths.

One of the primary objects of the invention is to provide a novel and improved tobacco feeder of this class which is capable of withdrawing tobacco from a mass in bulk, as in a hopper, and forming it into a relatively thick blanket, and 10 then progressively drawing out and thereby reducing the thickness of the blanket as the latter advances toward the point where it is to be spread or distributed whereby breakage of the tobacco into short lengths is reduced to a minimum and 15 the maximum amount of long length tobacco is obtained for the making of cigarettes or for similar purposes.

Another object is to provide a novel and improved tobacco feeder for cigarette machines 20 which is capable of spreading or distributing the tobacco at a uniform rate and in properly prepared condition onto the traveling belt or other means which forwards the tobacco into the cigarette machine to be inclosed as a filler in the usual way in the cigarette paper.

Another object is to provide novel and improved means for effectively withdrawing a supply of long cut tobacco from a bulk thereof in a hopper or the like onto a drum and of discharging the 30 tobacco from the drum to a series of drawing rollers or the like which prepare the tobacco for proper spreading or distribution, while substantially avoiding breaking of the tobacco into short lengths, either when the tobacco is received by the drum and thereby removed from the hopper or when removed from the drum.

A further object of the invention is to provide 40 novel and improved means for agitating or distributing the tobacco in the hopper while the tobacco is being withdrawn therefrom, thereby insuring withdrawal of the tobacco in the form of a blanket of substantially uniform thickness.

To these and other ends the invention consists in certain improvements and combinations 45 and arrangements of parts all as will be herein-after more fully described, the features of novelty being pointed out particularly in the claims at the end of this specification.

In the accompanying drawings:—

Figure 1 is a side elevation of a tobacco feeder constructed in accordance with the present invention, the same being connected to a cigarette machine;

Figure 2 is an end elevation of the improved

tobacco feeder, showing a portion of the cigarette machine in side elevation;

Figure 3 is a detail sectional view of the rollers for feeding the tobacco into the cigarette machine;

Figure 4 is a vertical section through the tobacco feeding drum and drawing rollers on an enlarged scale taken on the line 4—4 in Fig. 2;

Figure 5 is a detail vertical section through the series of drawing rollers shown in Fig. 4 but on an enlarged scale, showing the driving means for such rollers;

Figure 6 is a detail perspective view of the series of drawing rollers showing the relative arrangement thereof and the driving means therefor;

Figure 7 is a section taken diametrically through one end of the tobacco feeding drum;

Figure 8 is a vertical section taken on the line 8—8 in Fig. 7;

Figure 9 is a detail perspective view of one end of one of the rotatable shafts carried by the tobacco feeding drum and provided with the tobacco feeding pins;

Figure 10 is a side elevation of another embodiment of the tobacco feeder constructed in accordance with the present invention;

Figure 11 is an elevation of the structure shown in Fig. 10 as viewed from the left hand side thereof; and

Figure 12 is a detail view of the tobacco agitating and distributing members.

Similar parts are designated by the same reference characters in the different figures.

Tobacco feeders according to the present invention are adapted for use generally in all instances where the feeding of long cut tobacco, such as that used as the filler of cigarettes, is to be fed from a mass in bulk and drawn out into a thin sheet of uniform thickness, the invention 40 being however more particularly adapted for feeding long cut tobacco to cigarette machines whereby the tobacco is fed to such machines in a condition which enables it to form cigarette fillers of substantially uniform volume and density, the tobacco being fed and prepared according to the present invention with less breakage of the tobacco into short lengths than heretofore in cigarette feeders of the kinds previously used.

The preferred embodiments of the invention are shown in the accompanying drawings and will be herein-after described in detail, but it is to be understood that the invention is not restricted to the precise structures shown since equivalent con-

structions are contemplated and such will be included within the scope of the claims.

In the present instance, the improved tobacco feeder is shown applied to a cigarette machine of 5 well-known construction, for feeding the tobacco thereto to form the fillers for the cigarettes, the cigarette machine, a portion of which is shown, comprising a table 1 over which a strip of paper 2 to form the cigarette wrappers is fed, in the 10 form of a continuous sheet, from a roll 3, 4 being the stamping or printing device usually employed for stamping or printing the name or the like on the cigarette wrappers. A guide 5, having downwardly convergent walls, is mounted in the feeder machine above the path of the paper strip 2, for feeding tobacco onto the paper strip preparatory to the formation thereof into a rod from which the cigarette filler is to be formed. Beyond the tobacco guide 5 are located the sealing 15 and inclosing mechanisms 7 and 8 which may be of the usual construction commonly used in cigarette machines, and since these mechanisms and also the cutter mechanism beyond them which cuts the cigarettes into proper lengths are of the 20 usual and well known construction and they form no part of the present invention detailed description thereof is deemed unnecessary. The tobacco is introduced continuously into the top of the guide 5 by a roller 10 mounted above it and 25 having pins projecting from its periphery, and by a smooth faced roller 11 which is mounted above the roller 10, the latter roller being mounted on a shaft 12 having a sprocket wheel 13 fixed thereon over which passes a chain 14 which is 30 driven continuously in a manner which will be hereinafter described. The tobacco is fed between the rollers 10 and 11 by an endless traveling belt 15 the upper end of which passes around an idler roller 16 adjacent to the rollers 10 and 11 35 so that the tobacco advanced on the upper side of this belt will be introduced between the rollers 10 and 11. The roller 11 presses the tobacco so introduced onto the pinned surface of the roller 10, and the rotation of the latter roller carries the tobacco into a position above the guide 5. A 40 winnowing roller 17 is mounted above the guide 5 at one side of the roller 10, the roller 17 having pins projecting from its periphery and arranged to operate in the spaces between the pins on the 45 roller 10, the rollers 10 and 17 rotating in the same direction, as indicated by the arrows in Figure 3 whereby the tobacco pressed on the pinned surface of the roller 10 by the roller 11 will be removed therefrom by the winnowing roller 50 17 which revolves at relatively high speed and the tobacco will be thereby thrown downwardly into the guide 5. The winnowing roller is mounted on a shaft 18 to which is fixed a pulley 19 and this pulley is driven by a belt 20, this belt being 55 driven by a pulley 20^a fixed on a shaft 33 hereinafter described. The pressing roller 11 is driven at equal speed but in the opposite direction to that of the roller 10 by a gear 21 fixed on the shaft 12 of the roller 10 and meshing with a gear 60 22 fixed on the shaft 23 of the roller 11.

The endless continuously traveling feed belt 15 is driven from a roller 25 around which it passes, this roller being fixed on a shaft 26 journaled in suitable bearings in the frame of the cigarette 65 feeder machine, the shaft 26 being driven by a sprocket wheel 27 fixed thereon and cooperating with the chain 14, the latter passing around the sprocket wheel 13 which drives the roller 10 and around a sprocket wheel 96 on a shaft 95, herein- 70 after described. A shaft 30 is connected by gears

31 to a shaft 32 suitably journaled in the frame of the machine and the latter shaft is driven from a shaft 33 in the machine frame by oppositely positioned friction cones 34 and 35 fixed on the shafts 32 and 33 and connected by a crossed 5 belt 36 whereby the shaft 32 may be driven in the proper direction and at the proper speed. The shaft 33 is driven by a sprocket wheel 37 fixed thereon and a cooperating sprocket chain 38 from a sprocket wheel 39 mounted on a shaft 40, 10 this shaft being suitably journaled in the frame of the cigarette machine and being driven by a sprocket wheel 41 fixed thereon, a cooperating sprocket chain 42 and a sprocket wheel 43, the latter being fixed on or connected to the shaft of 15 an electric motor 44 which serves to drive the cigarette machine and feeder. The cigarette machine is driven from a shaft 45 having a sprocket wheel 46 fixed thereon and cooperating with a chain 47, the latter cooperating with a sprocket 20 wheel 48 on the shaft 40. Clutches 49 and 50 are mounted on the shaft 40 and are operable to connect the sprocket wheels 39 and 48 to the shaft 40 to be driven thereby so that the cigarette machine and the feeder may be driven simultaneously in proper timed relation or one independently of the other.

The tobacco feeder as shown in the present instance is adapted to be mounted on the frame 55^a of the feeder machine in a position to spread or distribute the tobacco onto the feed belt 15 so that the latter will carry the tobacco into the cigarette machine in the manner hereinbefore described. Preferably and as shown, the improved feeder comprises a frame 56 which is adapted 35 to fit against and to be bolted or otherwise secured to standards 57 which project upwardly from and form parts of the main frame of a well known type of cigarette feeder machine, the frame 56 embodying side members as shown in Figure 2, and said frame supporting a suitable tobacco receiving hopper 58 at the top thereof. Between the side members of the frame 56 and below the hopper is mounted a rotatable tobacco feeding drum or cylinder 60. As shown, this drum 40 comprises a cylinder having a series of shafts 61 extending longitudinally thereof and suitably spaced around its circumference. A circular end plate 62 is fixed to each end of the cylindrical drum and provides bearings in which the respective ends of the shafts 61 are mounted rotatably. Each of the shafts 61 carries a series of longitudinally spaced pins 63 which project therefrom in the same radial plane of each shaft and are equidistantly spaced longitudinally thereof, the pins of all of the shafts being aligned circumferentially around the periphery of the drum. The drum is rotatably mounted in the frame by a shaft 64 which extends axially through the drum and the end members 62 and is keyed or otherwise fixed thereto, this shaft being journaled in one side of the frame 56 and in a plate 65 which is bolted or otherwise removably fitted into the other side of said frame and has a sprocket wheel 66 keyed or otherwise fixed thereon for rotating 50 it in the direction indicated by the arrow in Figure 4.

The tobacco feeding drum as shown in Figure 4 is located directly beneath the open bottom of the hopper 58 so that it will receive tobacco therefrom, and means is provided for swinging the pins 63 so that they slant or incline toward the direction in which the drum rotates while these pins are passing across the bottom of the hopper and for reversing the slant or inclination of these pins 75

so that they incline away from the direction of rotation of the drum before they reach the point where the tobacco is discharged from the drum. The means shown in the present instance for so swinging the pins comprises cranks 67 which are fixed on the ends of the pin carrying shafts 61 and have rollers 68 on their free ends which travel in a cam groove 69 of appropriate shape and which may be formed in the plate 65, as shown. 5
 10 As will appear from Figure 4, the cam groove 69 has an outer or high-throw portion 69^a in which the rollers 68 on the pin carrying shafts travel while they pass beneath the hopper and an inner or low-throw portion 69^b in which the rollers on 15 the pin carrying shafts travel while such shafts are passing the point of discharge of the tobacco from the feeding drum, so that the pins 63 will slant or incline forwardly and thus engage and effectively withdraw the tobacco from the hopper, 20 and before reaching the discharge point, the inclination of the pins will be reversed, thus facilitating the removal of the tobacco from the periphery of the drum.

In order to agitate the tobacco contained in 25 the hopper to prevent clogging thereof, an agitator 70 is provided as shown in Figures 1, 2 and 4, this agitator comprising a pair of chains 71 arranged in parallelism and passing over sprocket wheels 72 and 73 fixed on a pair of upper and 30 lower shafts 74 and 75 mounted in suitable bearings at the side of the hopper toward which the pins 63 move. A series of bars 76, preferably of stainless steel, extend transversely between the chains 71 and are secured to the successive corresponding links thereof, these bars traveling upwardly along the inner side of the wall 58^a of the hopper as the sprocket wheels 73 are rotated in the direction of the arrow in Figure 4, thereby exerting a lifting action upon the tobacco contained in the hopper and thereby preventing packing or bridging of the tobacco therein. A series of agitating and distributing arms 80 are also preferably provided to operate in the bottom of the hopper above the tobacco feeding drum to insure the proper flow of tobacco to the drum and insure the formation of a blanket of tobacco of uniform depth or thickness on the circumference of the drum. These arms 80 are pivoted at the points 81 (Fig. 12) on a bracket 82 which 40 may be secured to the hopper at its outer side, these arms being connected by a link 83 which insures swinging movements thereof in unison, and one of the arms is provided with a crank arm 84 which is pivotally connected by a link 85 to a crank 86, the latter being fixed to the upper end of a shaft 87 which is journalled in suitable bearings 88 and is connected by bevel gears 89 to a shaft 90, the latter having a sprocket wheel 91 fixed thereon. During the operation of the feeder the agitating bars 76 rise continuously along the inner side of the hopper wall 58^a and the arms 80 swing to and fro across the bottom of the hopper above the feeding drum, the chains 71 of the agitator being driven continuously by a sprocket wheel 92 which is fixed on the shaft 75 and this sprocket wheel and the sprocket wheel 91 which drives the arms 80 being driven continuously at appropriate relatively low speed by a chain 93 which passes over a sprocket wheel 94 fixed on a shaft 95, this shaft being driven in a manner which will be hereinafter described, and having a sprocket wheel 96 fixed thereon and over which passes the chain 14 which drives the roller 10, and sprocket wheel 27 which drives the shaft 26, as hereinbefore described. 45
 50
 55
 60
 65
 70
 75

The tobacco, removed from the hopper and forming a blanket of the depth of the pins 63 on the periphery of the feeding drum, is removed from the drum by a roller 100 fixed on a shaft 101 and having a series of peripheral grooves 5 spaced axially to conform with the axial spacing of the pins 63 projecting from the periphery of the feeding drums so that these pins will pass through the spaces intervening the disk-like sections of the roller 100, thus enabling the peripheries of the disk-like sections of this roller to reach into close proximity to the periphery of the feeding drum, and the peripheries of the disk-like sections of the roller 100 are preferably corrugated, as shown at 102 in Figures 4 and 7. By 10 this construction and arrangement, when the blanket of tobacco on the periphery of the feeding drum reaches the discharge point adjacent to the roller 100, at which time the pins 63 will have reversed their directions of inclination, the 20 tobacco will be acted upon by the corrugated periphery of the roller 100 in a manner which will readily strip it from the drum, the roller 100 rotating continuously in the direction indicated by the arrow in Figure 4. In order to facilitate 25 the removal of the blanket of tobacco from the feeding drum, a cooperating roller 103 is mounted at the discharge point opposite to the roller 100 and is driven continuously in opposite direction to the direction of rotation of the roller 100. In 30 order to retain the blanket of tobacco on the feeding drum until it reaches the discharge point, a guard 106 may be placed between the side members of the frame 56 concentrically of the drum shaft 64, as shown in Figure 4. The shaft 35 104 for the roller 103 is driven in the direction indicated by the arrow in Figure 4 by a pair of gears 107 from a shaft 108, this shaft having a sprocket wheel 109 fixed thereon with which a chain 110 cooperates, this chain also cooperating 40 with a sprocket wheel 111 fixed on the shaft 101, and this chain in the present instance passes around the sprocket wheel 66 on the drum shaft 64 and thus serves to rotate the drum. The shaft 101 is driven by a sprocket wheel 112 which 45 is fixed thereon and cooperates with a chain 113, this chain passing around a sprocket wheel 114 fixed on a shaft 115, the latter having a relatively large gear 116 fixed thereon which meshes with a relatively small gear or pinion 117 fixed 50 on a shaft 118, and the latter having a relatively large gear 119 fixed thereon and meshing with a relatively small gear or pinion 120 fixed on a shaft 121. The shaft 121 has a sprocket wheel 122 fixed thereon with which a chain 123 55 cooperates, this chain passing around a sprocket wheel 124 fixed on the shaft 30. By the gearing just described, the rollers 100 and 103 will be driven in the relatively opposite directions indicated by the arrows in Figure 4 and at appropriate relatively low speed, and the feeding drum will be rotated in the direction indicated by the arrow in Figure 4 at relatively low speed. 60
 65
 70
 75

The present invention provides means for receiving the relatively thick blanket of tobacco, 65 removed from the drum 60 by the roller 100, and for drawing this blanket into a relatively thin strip in condition for spreading or distributing it on the feed belt 15. Such means comprises pairs of rollers 130, 130^a, 131, 131^a, 132, 132^a and 70 133, 133^a, these pairs of rollers being arranged in series in rows which converge in a direction from the point of discharge of tobacco from the feeding drum 60 so as to reduce the passageway between them as the tobacco advances there- 75

through, and the pairs of rollers are driven at progressively increasing speeds toward the narrower end of the passageway, and since these pairs of rollers are provided with pins on their peripheries, they will produce a drawing action upon the tobacco which will attenuate the blanket into a strip of diminishing thickness as the tobacco is advanced between these series of rollers. The rollers 130, 131, 132 and 133 are all driven in the same direction and in a direction to draw the tobacco between them and the co-operating rollers 130^a, 131^a, 132^a and 133^a, the latter rollers being driven in the opposite direction to that in which the first series of rollers are driven and in a direction to draw the tobacco through the passageway between the two series of rollers. The means for so driving these series of drawing rollers comprises sprocket wheels 134, 135, 136 and 137 which are fixed on the shafts of the rollers 130, 131, 132 and 133 and relatively larger gears 138 and 139 fixed on the shafts of the rollers 131 and 132 respectively, and a series of idler gears 140, 141 and 142, the idler gear 140 meshing with the gear 134 connected to the roller 130 and with the relatively smaller gear 135 connected to the roller 131, the larger gear 138 connected to the roller 131 meshing with the idler gear 141 and the latter meshing with the relatively small gear 136 connected to the roller 132, and the relatively large gear 139 connected to the roller 132 meshing with the idler gear 142, the latter meshing with the gear 137 connected to the roller 133, thus providing a drive of accelerating speed for the rollers 130, 131, 132 and 133 and causing all of the rollers of this series to revolve in the same direction and in the direction in which the tobacco advances. Similarly, the rollers 130^a, 131^a, 132^a and 133^a have gears 134^a, 135^a, 136^a and 137^a fixed to their shafts, the gear 134^a being larger than the gear 135^a, and relatively large gears 138^a and 139^a are connected to the rollers 131^a and 132^a respectively, and a series of idler gears 140^a, 141^a and 142^a are provided, the idler gear 140^a meshing with the gear 134^a connected to the roller 130^a and with the gear 135^a connected to the roller 131^a, the large gear 138^a connected to the roller 131^a meshing with the idler gear 141^a and the latter meshing with the small gear 136^a connected to the roller 132^a, and the large gear 139^a connected to the roller 132^a meshing with the idler gear 142^a and the latter meshing with the gear 137^a connected to the roller 133^a. The rollers 130 and 130^a are connected to rotate preferably at equal speed and in opposite directions so that they will advance the tobacco between them, by a pair of gears 143. The gearings thus provided between the series of pairs of rollers will drive the pairs of rollers successively at increasing speeds in a direction from the tobacco receiving toward the tobacco discharging end of the passageway between them, and all of the rollers will be rotated in directions to advance the tobacco between the pairs of rollers and, due to the progressively increasing speeds at which the successive pairs of rollers revolve, these pairs of rollers will produce a drawing action upon the tobacco which will attenuate the blanket of tobacco longitudinally into a stream of diminishing thickness, preparatory to the spreading or distribution of the tobacco upon the feed belt 15. The series of pairs of rollers may be driven from the shaft 101 by a gear 145 fixed on the shaft 101 and meshing with an idler gear 146^a, the latter meshing with a gear 146 fixed on the

same shaft with the roller 130. A curved guard 147 is preferably provided between the roller 103 and the roller 130^a to properly direct the blanket of tobacco removed from the drum 60 into the entrance to the passageway between the series 5 of pairs of drawing rollers.

By arranging the pins on the series of pairs of rollers so that they incline or slant backwardly from their directions of rotation, as shown, these rollers will effectively draw out and advance the 10 tobacco while reducing breakage of the tobacco to a minimum.

The strip of tobacco of reduced thickness, after passing through the converging passageway between the pairs of drawing rollers, is spread or 15 distributed onto the feed belt 15 of the cigarette machine by a spreading or distributing roller 150 which is located at the lower end of the passageway between the pairs of drawing rollers, the spreading or distributing roller 150 having pins 20 on its periphery to engage the tobacco strip, and this roller cooperating with a guard 151 which is concentric with the shaft 152 on which the roller 150 is mounted and extends partially 25 around the periphery of this roller to and slightly beyond a point directly beneath the center of this roller. The distributing or spreading roller 150 is driven by a pulley 153 fixed on the shaft thereof, a cooperating crossed belt 154 and a pulley 155, the latter fixed on the shaft 33, in the direction 30 of the arrow in Figures 4 and 5 and at a sufficient speed to throw the tobacco from the guard 151 and distribute it evenly upon the feed belt 15. In order to insure the entrance of the tobacco between the distributing roller 150 and 35 the guard 151, a pin roller 156 is preferably provided adjacent to the periphery of the roller 150 and at the entrance to the guard 151, this pin roller being driven in the direction indicated by the arrow in Figure 4 by a gear 156^a connected 40 to this roller and an idler gear 158 which meshes therewith and with the gear 157 connected to the roller 133.

In the embodiment of the invention shown in Figures 1 to 9 inclusive, the series of pairs of 45 tobacco drawing rollers are arranged vertically and substantially directly beneath the tobacco feeding drum 60 but these series of pairs of drawing rollers may be inclined from a side of the tobacco feeding drum, as shown for example in 50 Figure 10, the construction and mode of operation being the same as that already hereinbefore described. In the embodiment of the invention shown in Figures 10 and 11 the swinging agitating and distributing arms 80 are constructed and 55 arranged as hereinbefore described with reference to the preceding figures, the shaft 87 however for driving these arms being shown in this instance as driven from the shaft 64 of the feeding drum 60 by bevel gears 160, and the feeding 60 drum 60 and the roller 103 in this instance being driven from the shaft 101 of the roller 100 by a chain 161 which passes around sprockets 162, 163 and 164 fixed on the shafts 101, 104 and 64 respectively. In this instance a sprocket wheel 65 165 is fixed on the shaft of the roller 130 and may be driven by a chain 166 connected to one of the shafts of the cigarette machine as for example a sprocket wheel fixed on the shaft 26. The hopper, according to the embodiment of the 70 invention shown in Figures 10 and 11, is provided with a suitable number of swinging agitating arms 170 fixed on a shaft 171 suitably journaled in the walls of the hopper and having a crank arm 172 fixed thereon and operatively connected 75

by a link 173 to a crank 174 fixed on the shaft 64 of the feeding drum, so that as the feeding drum rotates the arms 170 will sweep back and forth above the feeding drum and thereby prevent bridging or clogging of the tobacco and insuring the formation of a blanket of tobacco of uniform thickness on the periphery of the drum.

The operation of a tobacco feeder constructed in accordance with the present invention is as follows:—Assuming that the hopper is supplied with tobacco and that the various elements of the machine hereinbefore described are set into operation, the rotation of the tobacco feeding drum 60 in the direction indicated by the arrow in Figure 4 causes a relatively thick blanket of tobacco to be deposited on the periphery of this drum, and to cause such tobacco in blanket form to be withdrawn from the hopper under the action of the pins 63 which at this time are inclined forwardly or in the direction in which the drum rotates. As the rotation of the drum continues, advancing the blanket of tobacco with it, the inclination of the fingers 63 is reversed so that they slant away from the direction in which the drum is rotated, as shown at the lower side of the drum in Figure 4. As the blanket of tobacco reaches the roller 100, the latter rotating in the direction indicated by the arrow in Figure 4, strips the blanket of tobacco from the drum, assisted more or less by gravity, and the blanket of tobacco in relatively thick form then passes between the roller 100 and the cooperating oppositely positioned roller 103, and the blanket of tobacco then enters the converging passageway formed between the series of pairs of drawing rollers.

The series of convergently arranged pairs of drawing rollers, driven at successively increasing speeds, act on the blanket of tobacco to draw it out into a thinner strip, and when the tobacco reaches the lower or discharge end of the passageway between the drawing rollers, and has been drawn into a relatively thin strip. The spreading or distributing roller 150, which is driven at relatively high speed, then acts on the relatively thin strip of tobacco thus produced, throwing the tobacco in an evenly distributed manner onto the traveling feed belt 15. This feed belt advances the tobacco to the rollers 10 and 11, the tobacco passing between these rollers and being thrown from the roller 10 by the rapidly revolving roller 11, into the guide 5 of the cigarette machine, the tobacco thus introduced into the cigarette machine being deposited on the paper strip 2 and as the latter and the tobacco thereon advance, the usual mechanisms commonly used in cigarette machines may operate to form the cigarettes.

By forming a relatively thick blanket of tobacco on the feeding drum and providing the latter with pins which are spaced at substantial distances around its circumference, a large amount of tobacco is withdrawn from the hopper with minimum engagement of the drum teeth therewith, so that breaking of the long cut tobacco into shorter lengths, as takes place in tobacco feeders as heretofore constructed embodying rollers with more numerous teeth and in which the tobacco was deposited to a less depth thereon, is avoided or reduced to a minimum, and by providing the pairs of drawing rollers driven at successively increasing speeds, the relatively thick blanket of tobacco is drawn out into a sufficiently thin strip to enable it to be uniformly spread or distributed onto the feed belt which carries the tobacco into

the cigarette machine. For example, in tobacco feeders of this general class as heretofore used, much waste tobacco has resulted from the use of relatively sharp closely-spaced teeth or pins on the drum, the teeth having a tendency to clip the tobacco into short lengths as they pass through the mass of tobacco in the hopper after the drum has become loaded, which is objectionable to the manufacturers of cigarettes. Such objections are overcome by the present invention. By providing on the drum pins of, for example, two inches in length and spaced apart axially one and one-half inches and spacing the rows of pins two inches apart around the circumference of the drum, and providing a relatively light flow of tobacco to the drum, a saving of long tobacco many times greater than that possible with feed drums such as those heretofore used, employing pins or teeth one-quarter of an inch in length and spaced one-quarter of an inch apart axially and circumferentially of the drum, is accomplished. Although the tobacco is withdrawn from the hopper in the form of a thick blanket, of a thickness of for example two inches, this blanket is reduced to a thickness of for example one-half inch by the drawing action of the series of pairs of rollers of successively increasing speed, thus preparing the tobacco for spreading or distribution on the feed belt which conducts the tobacco into the cigarette machine. By pivoting the pins on the feed drum so that they are inclined forwardly or toward the direction of rotation of the drum while passing across the bottom of the hopper, the removal of a blanket of tobacco of full thickness from the hopper is insured, and by reversing the inclination of these pins before they reach the point where the tobacco is discharged from the drum, the tobacco can be removed effectively from the drum without obstruction by the pins.

I claim as my invention:—

1. A tobacco feeder comprising a hopper to contain a supply of tobacco, a feeding drum rotatably mounted adjacent to the hopper and having pins on its periphery to remove tobacco from the hopper and form it in a relatively thick blanket on the drum, a rotatable roller having a circumferentially grooved axially corrugated periphery located in close proximity to the periphery of the drum and operative to remove the blanket of tobacco therefrom, and means arranged to receive the blanket of tobacco from said roller and operative to draw the tobacco into a sheet of relatively reduced thickness.

2. A tobacco feeder comprising a hopper to contain a supply of tobacco, a feeding drum rotatably mounted adjacent to the hopper and having pins on its periphery to remove tobacco from the hopper and form it in a relatively thick blanket on the drum, means arranged to receive the blanket of tobacco from the drum and operative to draw the tobacco into a sheet of relatively reduced thickness, a distributing roller, a guard cooperative with the underside of the periphery of said roller and arranged to receive the sheet of tobacco of reduced thickness, and means for revolving said roller at a speed to throw the tobacco from the guard and distribute it evenly.

3. A tobacco feeder comprising a hopper to contain a supply of tobacco, a feeding drum rotatably mounted adjacent to the hopper and having pins on its periphery to remove tobacco from the hopper and form it in a relatively thick blanket on the drum, a rotatable roller grooved circumferentially to receive the pins on the drum and mounted with its periphery in close proximity to

the periphery of the drum for removing the blanket of tobacco therefrom, and means arranged to receive the blanket of tobacco from said roller and operative to successively draw it out longitudinally and form it into a sheet of reduced thickness.

4. A tobacco feeder comprising a hopper to contain a supply of tobacco, means for withdrawing the tobacco therefrom in the form of a relatively thick blanket, and series of pairs of rollers having aligned passageways between them, said series of rollers having means for driving them at successively higher speed and operative to draw the blanket of tobacco through said passageways and form it into a relatively thinner strip.

5. A tobacco feeder comprising a hopper to contain a supply of tobacco, means for withdrawing the tobacco therefrom in the form of a relatively thick blanket, and pairs of rollers providing a convergent passageway between them to receive the blanket of tobacco and having means for driving the successive pairs of rollers at progressively increasing speed.

6. A tobacco feeder comprising a hopper to contain a supply of tobacco, means for withdrawing the tobacco therefrom in the form of a relatively thick blanket, series of pairs of rollers having means for driving them at successively higher speed and operative to draw the blanket of tobacco into a relatively thinner strip, and a spreading roll located at the tobacco discharge end of the passageway between said pairs of rollers.

7. A tobacco feeder comprising a hopper to contain a supply of tobacco, a drum rotatably mounted with its periphery in communication with the hopper, series of pins rotatably mounted on the drum to project at different angles from the periphery thereof, and means for changing the angles of said pins during rotation of the drum.

8. A tobacco feeder comprising a hopper to contain a supply of tobacco, a drum rotatably mounted with its periphery in communication with the hopper, series of pins rotatably mounted on the drum to project at different angles from the periphery thereof, and means for setting said pins at a forward inclination to remove tobacco from the hopper and at a rearward inclination subsequently thereto.

9. A tobacco feeder comprising a hopper to contain a supply of tobacco, a drum rotatably mounted with its periphery in communication with the hopper, series of pins rotatably mounted on the drum to project at different angles from the periphery thereof, means for removing tobacco from the drum, and means for inclining said pins forwardly while passing the hopper and for inclining said pins rearwardly prior to reaching said tobacco removing means.

10. A tobacco feeder comprising a hopper to contain a supply of tobacco in bulk and having a

discharge opening in its lower portion, and a drum rotatably mounted with its periphery adjacent to said discharge opening and having rows of pins rotatably mounted on its periphery to project forwardly and rearwardly of the direction of rotation of the drum.

11. A tobacco feeder comprising a hopper to contain a supply of tobacco in bulk and having a discharge opening in its lower portion, a drum rotatably mounted with its periphery adjacent to said discharge opening and having rows of pins rotatably mounted on its periphery to project forwardly and rearwardly of the direction of rotation of the drum, and means for setting said pins in forwardly inclined position while passing said discharge opening and in rearwardly inclined position after passing said opening.

12. A tobacco feeder comprising a hopper to contain a supply of tobacco in bulk and having a discharge opening in its lower portion, a drum rotatably mounted with its periphery adjacent to said discharge opening and having rows of pins rotatably mounted on its periphery to project forwardly and rearwardly of the direction of rotation of the drum, a cam, and cranks connected to the respective rows of pins and cooperative with said cam during rotation of the drum for setting said rows of pins in the different inclined positions.

13. A tobacco feeder comprising a hopper to contain a supply of tobacco in bulk and having a discharge opening in its lower portion, a drum rotatably mounted with its periphery adjacent to said discharge opening and having rows of pins rotatably mounted on its periphery to project forwardly and rearwardly of the direction of rotation of the drum, and agitating means mounted in the hopper to operate above the discharge opening therein.

14. A tobacco feeder comprising a hopper to contain a supply of tobacco in bulk and having a discharge opening in its lower portion, a drum rotatably mounted with its periphery adjacent to said discharge opening and having rows of pins rotatably mounted on its periphery to project forwardly and rearwardly of the direction of rotation of the drum, and means mounted in the hopper and operative to lift the tobacco therein above the drum.

15. A tobacco feeder comprising a hopper to contain a supply of tobacco in bulk and having a discharge opening in its lower portion, a drum rotatably mounted with its periphery adjacent to said discharge opening and having rows of pins rotatably mounted on its periphery to project forwardly and rearwardly of the direction of rotation of the drum, and agitating arms mounted in the hopper and operative to-and-fro in a plane above the drum to distribute the tobacco uniformly thereto.

JOHN T. DALTON.
